UNITED STATES PATENT OFFICE.

BEVERLY ROPER, OF ATLANTA, GEORGIA.

VELOCIPED.

SPECIFICATION forming part of Letters Patent No. 332,005, dated December 8, 1885.

Application filed May 15, 1885. Serial No. 165,626. (No model.)

To all whom it may concern:

Be it known that I, BEVERLY ROPER, a citizen of the United States, residing at Atlanta, in the county of Fulton and State of Georgia, have invented certain new and useful Improvements in Velocipedes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in tricycles, and has for its object to facilitate their propulsion by means of a system of hand and foot levers and a crank-shaft having two cranks operated from the hand-levers and two cranks operated from the foot-levers.

20 The further object of the invention is to provide means whereby the guide-wheel of the vehicle is better enabled to resist the shocks resulting from contact with an obstruction.

The further object of the invention is to 25 provide means for returning the steering-bar into its normal position and with it the guide or steering wheel when moved out of said position for the purpose of changing the course of the vehicle.

30 The invention has for its further object to provide increased facilities for carrying bundles or packages on the vehicle.

Referring to the accompanying drawings, Figure 1 is a top plan view, the seat being shown in dotted lines, of my improved tricycle. Fig. 2 is a central longitudinal section thereof, the steering-wheel being shown in full lines. Fig. 3 is a like view showing a modified arrangement of seat for the vehicle. Fig. 4 is a detached sectional view of the crank-shaft, showing the position of the cranks operated by the foot-levers relatively to the position of the cranks operated by the hand-levers. Fig. 5 is a detached end view showing the arrangement of the steering-wheel, and Fig. 6 is a perspective view of the upper portion of one of the foot-levers.

A indicates the frame, which by preference is made of metal, though it may be made of

wood, and of such form as to accommodate 50 and support the driving mechanism and the driver.

B are the main driving-wheels, constructed substantially like the wheels of vehicles of this class, and are keyed to opposite ends of 55 the driving or crank shaft C, that has its bearings in the side bars of the frame A. The crank-shaft C has four cranks, C' C' C' C', said cranks being formed on the shaft on opposite sides of a central portion, C³, Fig. 1. The 60 two cranks C', on opposite sides of said central space, C³, are connected with and operated from foot-levers D. The latter levers are two-armed levers pivoted on cross shafts or bars A' of the frame, the upper arm, D', being bent, 65 as shown, into the form of a loop, d', to the end of which is secured a stirrup, d, for the driver's foot, his heel resting on the bend d' of the arm D' of lever D. The lower arm, D², of foot-lever D is connected to the correspond- 70 ing arm, f', of a two armed lever, F, pivoted to a cross shaft or bar, a, by means of a connect- 75 ing-rod, F', and the upper arm, f, of lever F is connected by a rod, E, to a crank, C', of shaft C, the connection of both foot-levers with the crank-shaft being substantially the same.

The cranks C' are connected by means of rods H' to the lower arm, h', of the hand-levers H, which, like the foot-levers, are also two- 80 armed levers, the upper arm, h, constituting the lever-arm proper, from which the cranks C' are operated. Said levers are pivoted on short shafts or bars A², secured to the side bars of the frame, and a short bar, A³, connected with 85 the cross-girt A⁴.

It will be observed that by the arrangement of foot-levers and connections and their combination with the hand-levers and connections I reduce the power required to drive the vehicle to a minimum, as I obtain a much greater leverage in the arrangement of foot-levers de- 90 scribed than by any other arrangement heretofore adopted for this purpose. It will be further observed, and as plainly shown in Figs. 95 1 and 4, that the relative arrangement of the cranks is such that the two pairs can never reach their dead-centers simultaneously, one

pair of cranks being always slightly in the lead of the other pair, or, in other words, when the cranks of the hand-levers have reached one of their dead-centers those of the 5 foot-levers have passed beyond their dead-centers, thus insuring always an easy start of the vehicle.

If desired, all the cranks may be arranged so as to slightly lead one another and the same 10 result obtained.

I is the steering-bar, pivoted on the cross-girt A⁴ of the frame, and i i are the operating-handles, projecting laterally from the upper end thereof, to which arms are secured the 15 steering lines or chains K. At the foot of the bar I are secured short studs or pins i' i', that project from a square enlarged portion, I', of the bar I, on opposite sides thereof, and L L are springs, one end of which is secured to 20 the cross-girt A⁴, while their free ends bear upon the front face of the enlarged part I' of bar I. When said bar is turned to steer the vehicle, the studs i' impinge upon the free ends of the springs L and force them away from 25 the bar, and when the latter is released said bar is returned to its normal position by the springs, as will be readily understood.

A⁵ A⁵ are standards, bolted or otherwise secured to the short bars A³, and A⁶ A⁶ are like 30 standards secured to the side bars of the frame near its rear end, to which bars is secured the seat M. This seat M has a foot-board, m, that is slotted for the passage of the foot-levers, said foot-board being seated in uprights or 35 standards A⁵ A⁵, to which it is secured. The seat M is formed on a box, m', that projects rearwardly over the crank-shaft, and is secured to a cross-girt, A⁷, bolted to uprights A⁶.

It will be seen that by the described arrangement of seat a receptacle is provided of 40 quite a great carrying capacity, capable of holding more than any other receptacle or carrying device heretofore provided for this class of vehicles, and without interfering in the 45 least with the operating devices.

Instead of connecting the seat with the receptacle, and supporting the latter by rigid supports from the frame, the seat may be supported from springs and the receptacle may 50 be suspended from the seat, as shown in Fig. 3, the seat M being supported at a proper elevation with respect to the operating-levers D H from springs M', secured thereto and to the side bars of the frame.

55 Underneath the seat is secured a rod, N, whose ends have hooks n, from which is suspended a basket or other receptacle, m, that hangs or may hang immediately above the central portion, C³, of the crank-shaft, and as 60 this portion may in practice have a length of nine inches a basket of that width may be supported from the seat, and as the latter is at a considerable distance above and in front of the crank-shaft a comparatively long and deep 65 basket can be employed, together with a seat

that will hold two persons, or said basket or receptacle may extend quite across the entire vehicle, as shown in dotted lines in Fig. 1.

O is the steering-wheel, whose axle rotates in bearings formed in a bail or cross-head, P, 70 to which is secured one end of the steering-rod O'. The latter has cross-arms o', to which the steering-lines K are secured. The rod O' is pivoted in a bearing formed between the ends of the side bars of the frame A, as more 75 plainly shown in Figs. 1, 2, and 3.

In vehicles of this class, which are generally constructed as light as possible, the steering-rod of the wheel O whenever said wheel accidentally runs against an obstruction is subjected to very severe strain, and is frequently either bent so as to become inoperative or broken off at a point below its bearings in the frame. To avoid this, I employ the following devices: Q is a thrust-bar that is forked, the 85 arms q of which are mounted on the steering-wheel axle o². The end of the thrust-bar rides in a slotted segment, J, secured either to the side bars of the frame A or, as shown, to bracket-arms R, depending from said side bars. 90 The bar is shouldered on opposite sides of that portion which lies in the slot of the segment, as shown at q' q². It is obvious that when the wheel O runs against an obstruction the shock, instead of being sustained by the 95 steering-rod O', is taken up by the thrust-bar and transferred to the slotted segment, so that said rod cannot sustain any injury.

T indicates the guards applied to the ends of the side bars of the frame to prevent the 100 tilting backward of the vehicle. Said guards may be arranged as shown in Fig. 1, and a trailing-wheel, U, mounted thereon, or separate guards may be employed, as shown in Figs. 2 and 3.

I am aware that it is not broadly new to arrange cranks on crank-shafts so that one crank will lead the other or others; but I am not aware that such arrangements have been applied to the class of vehicles described in 110 combination with the system of levers set forth. I am also aware that springs have been applied to the steering-wheel of this class of vehicles to bring said wheel into its normal position after displacement. It is obvious, 115 however, that when so applied the springs are constantly subjected to strain at each slight deviation of said wheel from a straight course, and that such springs in a very short time become unserviceable.

Having now described my invention, what I claim as new is—

1. The combination of the crank-shaft C, having cranks C' C' and C² C², of the foot-levers D, levers F, and connecting-rods F' E, the 125 hand-levers H, and connecting-rods H', as described.

2. The combination, with the steering-wheel O and the forked bar Q, the arms q of which are mounted on the wheel-axle, said bar hav- 130

ing at its end shoulders $q' q^2$, of the slotted segmental guide-plate R, as described, for the purpose specified.

3. In a velocipede, a foot-lever, D, having a stirrup, d, and constructed to form a heel-rest, d^2 , as described, for the purpose specified.

4. The combination, with the frame A, springs M', and seat M, of a receptacle, m,

(basket or other,) suspended from said seat, as shown, and for the purpose specified.

In testimony whereof I affix my signature in presence of two witnesses.

BEVERLY ROPER.

Witnesses:

W. E. BOULTER,
HENRY ORTH.
